UNITED STATES PATENT OFFICE.

RAYMOND C. BAIRD, OF OMAHA, NEBRASKA, AND EUGENE E. SNELL, OF MOUNT CLEMENS, MICHIGAN.

RADIOCIRCUIT.

Application filed July 11, 1927. Serial No. 205,023.

(GRANTED UNDER THE PROVISIONS OF THE ACT OF MARCH 3, 1883, AS AMENDED BY ACT OF APRIL 30, 1928, 22 STAT. L., 625.)

The invention described herein may be manufactured and used by or for the Government for governmental purposes, without the payment to us of any royalty thereon.

5 This invention relates to a system for radio reception and one of its objects is to provide an arrangement of the character indicated having facilities for effecting rectification and subsequent amplification of 10 the positive and negative phase characteristics of the signal impulses.

Another object of this invention is to provide a radio receiving circuit in which the plate and grid of the detector tube are both 15 connected to the input circuit and both carry the same plate voltage, the respective currents from plate to filament and grid to filament being alternately established in accordance with the change of phase of the input circuit.

20 Another object of this invention is to provide a radio system wherein the circuits from plate to filament and grid to filament both include the primary of an audio transformer so that the rectification currents may 25 be suitably impressed upon the succeeding stages of audio frequency.

Another object of this invention is to provide a system of the character specified which is non-regenerative, highly selective, 30 exceptionally sensitive and possesses unusual qualifications as to tone and range.

With these and other objects in view this invention consists in certain novel details of construction, combination and arrangement of parts to be more particularly hereinafter set forth and claimed.

Briefly stated, this invention consists of a suitably tuned input circuit, (including in the present instance one stage of radio 40 frequency,) a detector and one or more stages of audio amplification, the plate and grid of the detector being inductively coupled to the input circuit and provided with the same value B battery potential so that 45 as the phase characteristics of the input change, a current will be alternately established from plate to filament and from grid to filament. These circuits each include the primary coil of the audio transformer for the 50 first stage of audio amplification, consequently, regardless of which circuit is functioning one or the other will transmit its current to the various stages of audio amplification.

Referring more particularly to the accompanying drawings:

55 Fig. 1 is a diagrammatic view of the system for radio reception constituting the subject matter of this application, and

Fig. 2 is a diagrammatic showing of the fundamental components of the circuit.

60 Heretofore, double rectification of the signal impulse has been obtained through the use of two crystal detectors, but this arrangement is more or less objectionable owing to the disadvantages attending crystal utilization and it is therefore the aim and purpose of this invention to provide a 65 circuit in which double rectification is accomplished through the medium of a conventional audion tube.

70 The radio circuit which is diagrammatically shown in Fig. 1 comprises four audions A_1 , A_2 , A_3 and A_4 , which are so arranged as to give a stage of radio frequency amplification, but it is to be noted that variations 75 in the number of radio and audio amplification stages may be had without departing from the general principles involved.

75 The tubes involved in this circuit are of standard type containing therein a grid plate and filament, the filament of all tubes being connected in parallel to the bus lines B and B_1 which are fed from the positive and negative sides of "A" battery (1) or 80 any other convenient source of power.

85 The antenna circuit includes the antenna (2) lead-in (3), variable inductance L_1 and the ground line (4). The inductance coil L_1 is tuned to the frequency of the desired signal by the variable condenser C_1 , which is 90 placed in parallel with it.

95 The circuit of the grid G_1 of audion A_1 includes the conductor (5), the oscillatory circuit comprising the inductance L_1 and variable condenser C_1 , the ground line (4) and the conductor (5') which leads through the jack switch (6) to the negative bus wire B of the filament circuit, to the filament F_1 .

100 The plate circuit of audion A_1 is completed through the conductor (7), inductance coil L_2 , conductor (8) to the positive side of the "B" battery (10).

105 The grid and plate of the second audion constituting the rectifier are conductively united and inductively coupled to the coil

L_2 which is interposed in the plate circuit of the audion A_1 , the inductive coupling being effected through the series wound coils L_3 and L_4 connected by the conductor (10').

5 The coils L_2 and L_3 are wound on the same tubing but separated from each other, whereas the coil L_4 is wound on a smaller cylinder which is inserted within the larger.

The inductance L_3 is tuned by the variable 10 condenser C_2 which is placed in parallel to said coil. The coil L_3 and variable condenser C_2 are connected to the plate through the conductor (11). The coil L_4 is connected to the grid through the conductor (12), grid 15 leak (13), fixed condenser C_4 and conductor (14).

The grid leak (13) and condenser C_4 are in parallel with each other and placed between the grid G_2 and the intersection of 20 the conductor (12) and the conductor (15) which is connected to one side of the variable condenser C_3 , the other side thereof being connected to the plate terminal p_1 of the primary coil of the first audio transformer 25 T_1 through the conductor (16) and a portion of conductor (19).

Returning to the tuned inductance L_2 it will be noted that one terminal thereof is joined to the positive side of the "B" battery (17) through the conductor (18) thus permitting the same positive charge of this "B" battery to be impressed on both the plate P_2 and grid G_2 of the rectifying audion when there is no additional positive or negative incoming signal impulse.

The negative side of the "B" battery (17) is connected through conductor (17') to the " b_1 " terminal of the primary of the first audio transformer T_1 , which is bridged by 40 the fixed condenser C_5 . The plate terminal p_1 of the first audio transformer is connected through the conductor (19) to the filament terminal f_1 of the same, which in turn is connected to the positive side B of the filament circuit through the conductor (20).

The audions A_3 and A_4 which are utilized as amplifiers are connected in the ordinary cascade manner, that is the grids G_3 and G_4 of audions A_3 and A_4 are connected to the 50 grid terminals g_1 and g_2 of the secondary coils of the first and second audio transformers T_1 and T_2 the opposite terminals f_1 and f_2 being connected through the conductors (21), (22) and (20) to the negative 55 side of the filament circuit.

The plates P_3 and P_4 of these audions are respectively connected, through the primary of the second audio transformer T_2 and through the phone or speaker jack (6) to the positive side of the "B" battery (10).

For a better understanding of the operation of the detector, reference may be had to the diagram shown in Fig. 2.

60 The radio frequency output of the coil L_2 is inductively impressed upon the coils L_4

and L_3 whereupon, depending on the phase characteristic of the signal the path of the incoming current will be as follows: through the conductor (11) to the plate P_2 and through the conductor (15), condenser C_3 70 and conductors (16) and (17') to the primary of the first audio transformer T_1 , thence through conductor (19) and bus bar B to the filament F_2 , thereby establishing a "B" battery current through the conductors (19), (11), and plate P_2 and back to the negative side of the "B" battery through the filament F_2 , conductor (19), the primary of the first audio transformer and conductor (17').

When the phase characteristic of the signal is in the opposite direction the path of the incoming current will be through the conductor (12), grid leak (13), condenser C_4 , conductor (14) and to grid G_2 , and 85 through conductor (18), the "B" battery (17), conductor (17'), primary of the first audio transformer T_1 , conductor (19), busbar B and to the filament F_2 , thereby establishing the "B" battery current through the conductor (18), coils L_3 and L_4 , conductor (12), grid leak (13), conductor (14) and to the grid G_2 and back to the negative side of the "B" battery through the filament F_2 , busbar B, the conductor (19), the 95 primary of the first audio transformer and conductor (17').

It is readily seen from the above operation that the detector functions alternately in rectifying the positive and negative incoming impulses.

In conclusion it will be manifest this system enables utilization of a portion of the radio frequency impulse which is ordinarily discarded and enables this double rectification to be performed through the medium of the conventional audion tubes. Moreover, by including the primary coil of the audio transformer in plate and grid circuit amplification is obtained for both the positive and negative phase characteristics of the input oscillation.

Having described our invention, what we claim as new and wish to secure by Letters Patent is:

1. In a radio receiving system an input circuit, a detector including plate, grid and filament, means for impressing the input oscillations across both grid and filament and plate filament, such means including a 115 trio of inductively associated coils, two of the latter being series connected and means for impressing a constant voltage of corresponding value on both plate and grid.

2. In a radio receiving system an input 125 circuit, a detector including plate, grid and filament, means for impressing the oscillations of the input across grid and filament and plate and filament, means for impressing a constant voltage of equal value on 130

both plate and grid, an amplifying circuit including an audio transformer the primary of said transformer being included in both the plate and grid circuit of the detector.

- 5 3. In a radio receiving system an input circuit, a detector including plate, grid and filament, means for impressing the input oscillations across grid and filament, plate and filament, such means including a plurality of inductively coupled coils, means for impressing a constant voltage equally on both plate and grid, an amplifying circuit, a transformer therefor, the primary of said transformer being included in the
- 10 15 plate and grid circuits of the detector.
- 15 4. In a radio receiving system an input

circuit, a detector including plate, grid and filament, means for impressing the input oscillations across grid and filament, plate and filament, such means including a trio 20 of coils inductively associated, one of said coils being in the input circuit, the remaining coils being series connected and arranged in the plate and grid circuits, means for impressing a constant voltage equally 25 on both plate and grid, an amplifying circuit, a transformer therefor, the primary of the transformer being in both plate and grid circuit.

RAYMOND C. BAIRD.
